TANK OUTLET UNIT

Romus Soucek, Whittier, Calif., assignor to Vultee Aircraft, Inc., Vultee Field, Calif., a corporation of Delaware

Application February 20, 1942, Serial No. 431,692

8 Claims. (Cl. 137—21)

The present invention relates generally to outlet units for tanks. More particularly the invention relates to that type of outlet unit which is for use in connection with a tank for supplying oil, fuel, or other liquid, to one of the operating parts of an airplane, such, for example, as the propeller driving engine and comprises a valve housing connected to the normal bottom of the tank and having a first inlet in communication with the tank interior at a point directly above the normal tank bottom, a second inlet leading to the tank interior at a point beneath the normal top of the tank, and an outlet leading from the discharge ends of the two inlets to an engine driven pump, and also comprises a gravity responsive valve element which is disposed within the housing, operates automatically to establish communication between the first inlet and the outlet and close the second inlet during normal flight maneuvers of the airplane and also to close the first inlet and open the second inlet in connection with inverted flight of the airplane, and hence serves to provide an uninterrupted flow of liquid to the engine regardless of the position of the tank and, in addition, to form a seal for preventing the pump from sucking air through the inlet having its inlet end above the surface of the liquid in the tank.

One object of the invention is to provide a tank outlet unit of this type which is an improvement upon, and has certain advantages over, previously designed units of the same general character and for the same purpose.

Another object of the invention is to provide a tank outlet unit of the type and character under consideration in which the valve housing has a normally downwardly facing valve seat at the discharge end of the first inlet and a normally upwardly facing valve seat at the discharge end of the second inlet and beneath and in spaced relation with the downwardly facing seat, and the gravity responsive or actuated valve element or means for connecting the outlet to either inlet, depending upon the position of the tank, is in the form of a single ball type valve which is mounted in the housing between the two seats and is so arranged with respect to the outlet that the impact pressure of the liquid flowing from the open inlet to the outlet acts against it in the same direction as the force of gravity and hence assures proper sealing of the valve with respect to the seat for the closed inlet.

Another object of the invention is to provide a tank outlet unit of the last mentioned char-

acter in which the ball valve constituting the gravity responsive or actuated valve means for selectively or alternately controlling the two inlets, depending upon the condition of tilt of the tank, is provided with a normally depending pendulum type weight which extends through the portion of the discharge end of the second inlet that is normally beneath the upwardly facing valve seat and serves so to transfer the center of gravity of the valve in connection with all angles of positive acceleration climb, dive and bank of the airplane that the center of gravity is so located as to cause the valve to remain properly seated against the lower or upwardly facing valve seat.

A further object of the invention is to provide a tank outlet unit of the type under consideration in which the inlet end of the second inlet is in the form of a standpipe which normally extends substantially vertically within the tank and has at its upper end a swivel type auxiliary inlet pipe section which extends slightly downwards during normal flight attitudes of the airplane and swings toward the normal top of the tank in connection with inverted flight of the airplane.

A still further object of the invention is to provide a tank outlet unit which is generally an improvement in the art and is characterized by simplicity of design and construction and efficiency of operation.

Other objects of the invention and the various advantages and characteristics of the present tank outlet unit will be apparent from a consideration of the following detailed description.

The invention consists in the several novel features which are hereinafter set forth and are more particularly defined by claims at the conclusion hereof.

In the drawings which accompany and form a part of this specification or disclosure and in which like letters and numerals of reference denote corresponding parts throughout the several views:

45 Figure 1 is a section showing an outlet unit embodying the invention in operative or connected relation with a tank for supplying oil to an airplane engine;

50 Figure 2 is an enlarged section showing the unit in the position which it assumes when the airplane is flying in an inverted manner;

55 Figure 3 is a side view of the improved unit; and

Figure 4 is a plan view illustrating in detail the swivel type connection for the swing type

pipe section at the inlet end of the standpipe constituting a part of the second inlet of the unit.

The outlet unit which is shown in the drawings constitutes the preferred form or embodiment of the invention. It is illustrated in connection with, and as forming a part of, a tank T for supplying oil to an airplane engine E. The tank, together with the unit, serves as part of an oil circulating system for the engine and comprises a continuous side wall t having an out-turned flange t¹ at the bottom margin thereof. The top or upper portion of the tank T is closed in any suitable manner, such, for example, as illustrated in Figure 1. The improved outlet unit is located at the normal bottom of the tank T and consists of a valve housing 5 and a gravity responsive or actuated valve 6.

The valve housing 5 is preferably in the form of a casting of aluminum or other suitable light material and has at the upper portion thereof a flat wall 7. This wall is shaped conformably to the bottom of the tank T and has the marginal portion thereof removably secured to the out-turned flange t¹ by bolts or other connecting devices. A gasket 8 is interposed between the marginal portion of the wall 7 and the out-turned flange t¹ in order to prevent leakage of oil between the bottom portion of the tank and the valve housing 5. The central portion of the wall 7 of the valve housing is provided with a pair of side by side comparatively short upstanding annular bosses 9 and 10. Both of these bosses lead downwards to, and communicate with, the interior of the valve housing. The boss 9 is disposed within the lower portion of the tank T and has a nipple 11 associated with it. This nipple extends normally substantially vertically and, together with the annular boss 9, constitutes a first or low level inlet 12 between the tank and the valve housing 5. The lower end of the nipple fits within the boss 9 and is removably secured to the latter by a screw thread connection 13. The outer periphery of the upper end of the nipple is provided with radially extending lugs 14 whereby the nipple may be turned relatively to the boss 9 in connection with attachment and removal. As shown in the drawings, the boss and nipple have a comparatively small combined length with the result that the first inlet 12 of the valve housing communicates with the tank interior at a point directly above the normal bottom portion of the tank. The lower end of the nipple 11 is beveled or chamfered so as to form a downwardly facing valve seat 15 at the lower or discharge end of the first inlet 12.

The interior of the valve housing 5 is provided with, and divided by, an integral step-shaped cross web 16. This cross web consists of a normally vertical lower part 17, a normally vertical laterally offset upper part 18, and a normally horizontal intermediate part 19 between and cross connecting the upper end of the lower part 17 and the lower end of the upper part 18. The intermediate part 19 of the cross web is located directly beneath and spaced from the first inlet 12 and has an upwardly extending valve seat 20 in axial alignment with the downwardly facing valve seat 15 at the lower discharge end of the first inlet 12. The upper part 18 of the cross web depends from the wall 7 of the valve housing at a point midway between the two bosses 9 and 10 and it, together with the bottom face of the intermediate part 19 and the immediately adjacent portion of the side wall of the valve hous-

ing, defines a J-shaped passage 21 between the boss 10 and the upwardly facing valve seat 20. The passage 21, the boss 10 and a normally vertically extending standpipe 22 constitute a second or high level inlet 23 for the valve housing 5. The upwardly facing valve seat 20 is at the discharge end of the second inlet 23, as clearly shown in Figure 3. The standpipe 22 is axially aligned with, and constitutes a continuation of, the annular boss 10. The lower end of the standpipe is provided with an outwardly extending right angle flange 24 and this is removably secured to the top face of the boss 10 by an annular series of cap screws 25. The upper end of the standpipe communicates with the interior of the tank T at a point directly beneath the normal effective top of the tank. The portion of the interior of the valve housing 5 that is between the annular boss 9 and the intermediate part 19 of the cross web 16 constitutes an outlet 26. This outlet communicates with the discharge ends of the first and second inlets 12 and 23 by way of the valve seats 15 and 20 and leads to, and discharges into, a tubular outlet extension 27 at one side of the valve housing 5. A pipe or conduit 28 extends between, and is connected to, the outlet extension 27 and the suction side of a pump 29. The latter is associated with, and driven by, the engine E and operates in connection with operation of the engine to draw oil from the tank T via the outlet unit and supply it under pressure to the engine. The oil, after being delivered to the engine, is returned to the top of the tank T by way of a return pipe or conduit 30, including an oil cooler 31.

The valve 6 is ball shaped and serves selectively or alternately to close the valve seats 15 and 20, depending upon the position or degree of tilt of the tank T. It is loosely mounted in the outlet 26 and is movable back and forth between the two valve seats. As shown in the drawings, the valve 6 is so shaped that when in seated relation with either valve seat it forms an efficient seal or closure. When the airplane with which the engine E is associated is subjected to normal flight maneuvers or attitudes the valve 6, as shown in Figures 1 and 3, is caused by the action of gravity to seat against the upwardly facing valve seat 20 and close the discharge end of the second or high level inlet 23. The valve 6 is formed of any suitable material having a greater specific gravity than that of the oil which is supplied by the tank T to the engine via the improved outlet unit. When the valve is in seated relation with the upwardly facing valve seat 20 and the second or high level inlet 23 is hence closed, oil is permitted to flow from the tank to the outlet 26 via the first or low level inlet 12 which, as previously pointed out, communicates with the tank interior at a point adjacent the normal bottom of the tank. With such an arrangement of the valve the inlet 23 is effectively closed and hence should the upper end of the standpipe be above the level of the oil in the tank there is no likelihood of any air being drawn into the outlet 26. In the event that the body of the oil in the tank should be thrown away from the normal tank bottom, as is the case when the airplane assumes an inverted flight attitude, the valve 6, due to the action of gravity, moves into seated relation with the valve seat 15 and results in closing of the inlet 12 and opening of the inlet 23. When the inlet 12 is closed and the inlet 23 is open due to inversion of the airplane, oil is drawn into the outlet 26 via the inlet 23.

and the inlet 12 is sealed by the valve and hence no air is drawn into the outlet should the inlet end of the inlet 12 be above the level of the oil in the tank. By employing a single valve and valve seats which face one another and arranging the valve seats as shown in the drawings the impact pressure on the valve 6 due to the flow of oil into the outlet 26 acts in the same direction as the force of gravity and thereby assures proper seating characteristics so far as the valve is concerned. In this connection it is to be noted that when the valve 6 is in seated relation with the valve seat 20 due to the airplane being flown at normal flight attitudes the oil flowing into the outlet 26 via the inlet 12 impinges against the valve 6 and hence augments the action of gravity in maintaining the valve in seated relation with the valve seat 20. When the airplane is in an inverted attitude of flight and the valve 6 is hence positioned in seated relation with the valve seat 15 the oil flowing into the outlet 26 via the inlet 23 impinges against the valve and thus, together with the action of gravity, maintains the valve in proper or accurate seated relation with the seat 15. Due to the action of the valve 6 there is always an unrestricted or uninterrupted flow of oil into the outlet 26 regardless of the position or angle of tilt of the tank T and no air above the level of the body of the oil in the tank is permitted to be drawn into the outlet. In assembling the outlet unit the valve 6 is inserted into the outlet 26 via the annular boss 9 prior to connection of the nipple 11 to the boss. In the event that it is desired to remove the valve for inspection or repair purposes it is only necessary after removal of the unit from the tank to remove the nipple 11 from the boss 9. Upon removal of the nipple from the boss 9 the valve may be removed from the outlet 26 by inverting the valve housing 5.

The valve 6 is provided with a normally depending pendulum type weight 32. This weight comprises a stem 33 and a head 34. The upper end of the stem 33 is connected to the valve 6 and the lower end of the stem is connected to the central portion of the head 34. As shown in Figure 3, the stem extends radially with respect to the valve and projects through the short leg of the passage 21 constituting the discharge end of the second or high level inlet 23. The head 34 is disposed within a cylindrical or tubular extension 35 at the bottom of the valve housing 5. Such extension has an open bottom and this is normally closed by a plate 36 which is removably secured in place by an annular series of cap screws 37. When the plate 36 is removed from its normal or operative position oil may be drained from the second or high level inlet 23. The head 34 of the pendulum type weight 32 is disc-like so far as contour or conformation is concerned and is of less diameter than the inner periphery of the cylindrical extension 35 at the bottom of the valve housing 5 in order that the weight is free to move laterally to a limited extent. Preferably the weight 32 and the valve 6 are integral. The weight serves as a medium for holding the valve in seated relation with the seat 20 at the discharge end of the inlet 23 in connection with all angles of positive acceleration, climb, dive and bank of the airplane. If the airplane assumes a bank or a positive angle of dive or climb in connection with flight the pendulum type weight swings or moves within the extension 35 and so changes the center of gravity of the valve 6 that the valve is effectively and

efficiently maintained in seated relation with the normally upwardly facing valve seat 20. In the event that the airplane assumes an inverted flight condition or attitude the valve 6 moves into seated relation with the valve seat 15, as heretofore pointed out, and the pendulum type weight 32 moves in the direction of the intermediate part 19 of the cross web 17 in the valve housing 5.

In order to increase the efficiency of the unit 10 when the airplane is subjected to extremely severe operating conditions the standpipe 22 is provided at its upper end with an inlet type auxiliary pipe section 38. This pipe section normally extends slightly downwards, as shown in Figures 1 and 3, and is connected to the upper end of the standpipe 22 by a pivot or swivel type connection so that when the tank is inverted in connection with inverted flight attitude of the airplane it swings in the direction of the normally effective 15 top of the tank. The pivot or swivel type connection comprises an elbow 39 on the upper end of the standpipe 22 and a fitting 40 on the proximal end of the pipe section 38. The elbow 39 embodies a depending branch 41 and a laterally extending branch 42. The depending branch is connected by a screw thread connection to the upper end of the standpipe. The laterally extending branch 42 of the elbow fits within a 20 socket in the fitting 40. The fitting 40 and the laterally extending branch 42 of the elbow are 25 suitably maintained in seated relation and are so constructed that they effect communication between the inner end of the pipe section 38 and the upper end of the standpipe 22 while at the same 30 time they permit swinging movement of the pipe section relatively to the standpipe. A lug 43 on the fitting 40 and a pair of coacting lugs 44 on the laterally extending branch 42 of the elbow serve 35 to limit the swinging movement of the pipe section relatively to the standpipe. When the tank T is in its normal position the pipe section 38 extends slightly downwards from the upper end of the standpipe 22 as previously pointed out and as shown in Figures 1 and 3. If the level of the oil 40 in the tank is above the upper end of the standpipe, that is, above the upper end of the elbow 39 and the fitting 40, no air is permitted to be drawn into the outlet 26 even though the valve 6 is not in proper seated relation with the upwardly facing valve seat 20. Then the tank T is tilted upside down due to the airplane being flown in an inverted position the pipe section 38 swings away from the normal bottom of the tank with the result that the distal or inner end thereof is nearer to the bottom of the body of oil in the tank T. The pipe section 38 is formed of material having greater specific gravity than the oil in the tank and swings relatively to the standpipe 22 in response to the action of gravity.

The herein described tank outlet unit effectively and efficiently fulfills its intended purpose and is characterized by the fact that it is simple in design and construction and hence may be manufactured at a low and reasonable cost. It is further characterized by the fact that the valve and valve seat arrangement is such that the impact pressure of the oil flowing into the outlet 26 acts on the valve 6 in the same direction as the action of gravity and hence retains the valve in its closed or seated position.

Whereas the outlet unit has been described in connection with a tank for supplying oil to an airplane engine it is to be understood that it may be employed in connection with a tilttable tank for supplying other liquids. It is also to be under-

stood that the invention is not to be restricted to the details set forth since these may be modified within the scope of the appended claims without departing from the spirit and scope of the invention.

Having thus described my invention what I claim as new and desire to secure by Letters Patent is:

1. An outlet unit adapted for use in connection with a tilttable liquid containing tank and comprising means associated with the normal bottom of the tank and forming a J-shaped duct having the end of the short leg thereof communicating with the tank interior near said normal bottom and serving as a low level liquid inlet and the end of its long leg communicating with the interior of the tank at a point above the low level inlet and serving as a high level liquid inlet, a pair of spaced apart valve seats positioned in the short leg of the duct so that they face one another and constituting the discharge ends of the two inlets, respectively, means forming a liquid outlet leading from the space in the duct between the valve seats, and a single gravity responsive valve mounted loosely in said space and adapted to seat against either seat, depending upon the angular position of the tank.

2. An outlet unit adapted for use in connection with a tilttable liquid containing tank and comprising means associated with the normal bottom of the tank and forming a J-shaped duct having the end of the short leg thereof communicating with the tank interior near said normal bottom and serving as a low level liquid inlet and the end of its long leg communicating with the interior of the tank at a point above the low level inlet and serving as a high level liquid inlet, a pair of spaced apart valve seats positioned in the short leg of the duct so that they face one another and constituting the discharge ends of the two inlets, respectively, means forming a liquid outlet leading from the space in the duct between the valve seats, a single gravity responsive valve in said space adapted to seat against either seat, depending upon the angular position of the tank, and provided with a normally depending weight extending through the valve seat constituting the outlet end of the high level liquid inlet.

3. An outlet unit adapted for use in connection with a tilttable liquid containing tank and comprising means associated with the normal bottom of the tank and forming a J-shaped duct having the end of the short leg thereof communicating with the tank interior near said normal bottom and serving as a low level liquid inlet and the end of its long leg communicating with the interior of the tank at a point above the low level inlet and serving as a high level liquid inlet, a pair of spaced apart annular valve seats positioned in the short leg of the duct so that they face one another and constituting the discharge ends of the two inlets, respectively, means forming a liquid outlet leading from the space in the duct between the valve seats, and a single gravity responsive ball type valve in said space adapted to seat against either seat, depending upon the angular position of the tank and provided with a normally depending pendulum type weight extending through the valve seat constituting the discharge end of the high level inlet.

4. An outlet unit adapted for use in connection with a tilttable liquid containing tank and comprising a valve housing connected to the normal bottom of the tank and having a pair of vertically spaced valve seats therein facing

10 toward one another and forming a liquid outlet therebetween, open ended hollow means leading from the upper seat into the tank interior at a point adjacent said normal bottom and constituting a low level liquid inlet, a second open ended hollow means leading from the lower valve seat into the tank interior at a point an appreciable distance above said normal bottom and constituting a high level liquid inlet, and a gravity responsive valve loosely mounted in the outlet between the two valve seats and adapted to seat against either seat, depending upon the degree of tilt of the tank.

5. An outlet unit adapted for use in connection with a tilttable liquid containing tank and comprising a valve housing connected to the normal bottom of the tank and having a pair of vertically spaced valve seats therein facing toward one another and forming a liquid outlet therebetween, said housing also having a well type chamber directly beneath, and communicating with, the lower valve seat, open ended hollow means leading from the upper seat into the tank interior at a point adjacent said normal bottom and constituting a low level liquid inlet, a second open ended hollow means leading from the chamber into the tank interior at a point an appreciable distance above said normal bottom and constituting with said chamber a high level liquid inlet, and a gravity responsive valve in the outlet between the two valve seats adapted to seat against either valve, depending upon the angular position of the tank, and provided with a normally depending weight extending through the lower valve seat and into the chamber and arranged to swing or move universally to a limited extent in the chamber.

6. An outlet unit adapted for use in connection with a tilttable liquid containing tank and comprising a valve housing connected to the normal bottom of the tank and having a pair of vertically spaced annular valve seats therein facing toward one another and forming a liquid outlet therebetween, said housing also having means forming a cylindrical chamber beneath, and in communication with, the lower valve seat, open ended hollow means leading from the upper seat into the tank interior at a point adjacent said normal bottom and constituting a low level inlet, a second open ended hollow means leading from the chamber into the tank interior at a point an appreciable distance above said normal bottom and constituting a high level liquid inlet, and a gravity responsive ball type valve in the outlet between the two valve seats adapted to seat against either seat, depending upon the degree of tilt of the tank, and provided with a pendulum type weight extending through the lower valve seat and into the chamber and arranged to swing universally to a limited extent within said chamber.

7. An outlet unit adapted for use in connection with a tilttable liquid containing tank and comprising means adjacent the normal bottom of the tank forming an outlet, liquid conducting means leading from the outlet into the tank at a point adjacent said normal tank bottom and forming a low level liquid inlet, a standpipe having one end thereof communicating with said outlet and its other end leading into the tank interior at a point an appreciable distance above said normal bottom and constituting a high level liquid inlet, gravity responsive valve means operable automatically selectively to control the flow of liquid through the inlets to the

outlet according to the tilt position of the tank, and an auxiliary tubular inlet member connected to said other end of the standpipe and arranged to swing by gravity back and forth between the normal bottom and top of the tank in response to tilting of said tank.

8. An outlet unit adapted for use in connection with a tiltable liquid containing tank and comprising means adjacent the normal bottom of the tank forming an outlet, liquid conducting means leading from the outlet into the tank at a point adjacent said normal tank bottom and forming a low level liquid inlet, a standpipe in the tank having one end thereof communicating

5 with said outlet and its other end terminating adjacent the normal top of the tank, and constituting a high level liquid inlet, gravity responsive means operable automatically selectively to control the flow of liquid from the inlets to the outlet according to the tilted position of the tank, an auxiliary pipe section pivotally connected to said other end of the standpipe and arranged to swing by gravity back and forth between said normal bottom and top of the tank in response to tilting of the tank, and means for limiting swinging movement of said pipe section.

10 ROMUS SOUCEK.
